UNITED STATES PATENT OFFICE.

MARION R. JENKINS, OF BROWNING, MISSOURI.

TELEGRAPH-KEY.

SPECIFICATION forming part of Letters Patent No. 351,834, dated November 2, 1886.

Application filed October 16, 1885. Serial No. 180,093. (No model.)

To all whom it may concern:

Be it known that I, MARION R. JENKINS, a citizen of the United States, residing at Browning, in the county of Linn and State of Missouri, have invented certain new and useful Improvements in Telegraph-Keys; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to that class of telegraph-keys used for making and breaking circuit in sending Morse characters by hand; and it has for its objects to prevent the well-known "sticking" of the circuit-closing contacts, which is so great a hinderance of rapid and distinct sending; to relieve the operator's hand of the jarring, which is such an objectionable incident of the use of ordinary keys, and not infrequently results in paralysis; to facilitate the opening and closing of the circuit preparatory to use and disuse of the key, and to improve the general construction and arrangement of the parts of the key and its base.

In the accomplishment of these objects my invention consists in certain novel constructions and combinations of the parts composing the key, which may be fully understood from the following particular description in connection with the accompanying drawings, and the novel features of which will be definitely pointed out in the appended claims.

In the drawings, Figure 1 is a top view of my improved telegraph-key. Fig. 2 is a side elevation thereof. Fig. 3 is a partial section on the line $x-x$ of Fig. 1. Fig. 4 is a detail perspective view of the supplementary lever. Fig. 5 is an end view of the same, and Fig. 6 is an enlarged section on line $y-y$.

The letter A designates the non-conducting base, which supports all the other parts, and is round and flat or disk-like in shape, this form giving superior compactness and economy in construction. To this base are secured two metal posts, B B, provided with concave-tipped center screw-bearings, C C, which receive the conical tips of trunnions D D, which

project from opposite sides of a main key-lever, E. The short arm e' of this main lever is provided with an adjustable stop screw, f, which strikes upon a stop plate, g, and the long arm e is forced upward by a spring, h, the tension of which is regulated by an adjustable screw, i.

Under the main lever is arranged a supplementary lever, J, which operates in co-operation with said main lever. That end of the supplementary lever J which lies under the trunnions of the main lever is wide, as shown at j, and said lever has an opening or slot, j' , through which the spring h of the main lever reaches the base A clear of the supplementary lever. The supplementary lever at the widest portion of its inner end is provided with downwardly-projecting knife-edges k k , which rest in a shallow groove in a metallic bearing-plate, l, which is let into the base A, and between the knife-edges k k an opening is formed in the supplementary lever and fitted with the shank of a hard-rubber or other non-conducting button, l', through which is passed a metallic screw, m, the head of which is insulated from the under surface of the lever by a non-conducting washer, m'.

The upwardly-turned tip of the screw has a conical recess, which serves as a bearing for the conical tip of an adjustable screw or arm, N, which projects downward from the main lever E between its trunnions, so that when said main lever is oscillated on its trunnions, the screw or arm N will be vibrated and cause the supplementary lever to vibrate on its knife-edges. When the long arm of the main lever is depressed, the projecting arm of the supplementary lever rises to meet it, and a contact-point, q, of said lever below comes in contact with a similar point, q' , of the lever above, and the lower lever sinks as the upper lever is again to rise.

The binding-post p is connected with the bearing-plate l by a wire, (indicated by a dotted line at w ,) and the post p' is connected with the main lever E by a wire, w' , the supporting-post B', its screw-bearing, and the trunnion, which has its bearing in said screw. The posts p and p' are to hold the ends of line-wires. It will be seen, then, that the points q and q' of

the supplementary and main levers must be brought together to "make" and allowed to separate to "break" circuit, and as these contact-points are caused to travel toward and from each other, (instead of one being at rest and the other doing all the traveling,) they are not required to be adjusted so closely together for rapid transmission as is the case in ordinary keys but even when quite closely adjusted the levers so co-operate to open a space between them that even when the strongest current flows over the circuit the contacts will not "stick."

The non-conducting finger button or knob R of the main key-lever has a metallic shank, r, which screws up into the knob through the end of the lever, and to the lower end of this shank is secured a curved metallic spring-finger, s, which, by depressing the main lever and turning the knob, may be caused to project under the supplementary lever and hold the two levers in metallic contact, either by the touching together of their contact-points q and q' or by the metallic connection formed by the 25 spring itself. This will be the position of the levers when the key is not in use and the circuit is closed through it. By turning the button, say, one-fourth of a revolution, the spring may be caused to project laterally and release 30 the supplementary lever to open the circuit preparatory to using the key.

I prefer to mill or notch the periphery of the knob R, in order that it may be turned readily. By means of this knob and circuit-closing spring the operator avoids the manipulation 35 of a separate cut-out or circuit closing and opening device, such as commonly used with transmitting-keys.

The projecting arm of the supplementary lever J is slightly elastic and holds its contact-point q directly under the point q' of the main lever, so that when the point q' strikes the lower point the supplementary lever yields sufficiently to prevent that pounding action which, 45 in the old-style keys, communicates to the hand and arm of the operator a jarring, which becomes extremely disagreeable, and sometimes causes paralysis.

I do not limit my invention to the precise 50 construction and arrangement of the parts as

shown in my drawings, but reserve to myself, broadly, the right to arrange the two levers in any manner that will enable them to move in co-operation with each other for making and breaking the circuit, and I may provide either 55 one of these levers with a circuit-closing device for engaging and releasing the other preparatory to using and disusing the key.

What I claim is—

1. In a telegraph-key, the combination, with 60 each other, of the main and supplementary levers, connected and arranged, substantially as described, to alternately approach and recede from each other for making and breaking contact as the result of manipulation of the main lever.
2. The combination, with the pivoted main lever and the supplementary lever, of a retracting-spring for said main lever, the arm projecting downward from about the fulcrum-line of 70 said main lever, and loosely engaging, but insulated from, the supplementary lever at about the fulcrum-line of the latter, substantially as described.
3. The combination, with a main key-lever 75 having one arm provided with a circuit-closing contact-point, of a contact-point mounted upon an elastic lever and arranged to come in contact with that of the main lever, for the purpose set forth.

4. The combination, with the main and supplementary levers, arranged and mechanically connected and supported substantially as described, of a circuit-closing link or hook attached to one of said levers and arranged to engage and disengage the other.

5. The combination, with the pivoted supplementary lever, of the pivoted main lever having a rotary non-conducting finger-knob and a curved metallic spring connected with said knob and arranged to be thereby swung into or out of engagement with the supplementary lever, so as to establish metallic connection between said levers, essentially as set forth.

In testimony whereof I affix my signature in 95 presence of two witnesses.

MARION R. JENKINS.
